CLAIM

The ornamental design for a vibration platform exercise machine as shown and described.

DESCRIPTION

FIG. 1 is a top front perspective view showing the vibration platform exercise machine;

FIG. 2 is a rear top rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top front perspective view thereof, shown in use state; and,

FIG. 10 is a top front perspective view showing the vibration platform exercise machine in another environment.

The broken lines in the figures illustrate portions of the vibration platform exercise machine that form no part of the claimed design.

1 Claim, 10 Drawing Sheets
